(57) **CLAIM**

The ornamental design for a LED light, as shown and described.

DESCRIPTION

FIG. 1 shows a front view of a LED light showing our new design;

FIG. 2 is a rear view thereof;

FIG. 3 is a left-side view thereof;

FIG. 4 is a right-side view thereof;

FIG. 5 is a top view thereof;

FIG. 6 is a bottom view thereof;

FIG. 7 is a perspective view thereof;

FIG. 8 is a second perspective view thereof;

FIG. 9 is front view thereof, showing contour shading;

FIG. 10 is a rear view thereof, showing contour shading;

FIG. 11 is a left-side view thereof, showing contour shading;

FIG. 12 is a right-side view thereof, showing contour shading;

FIG. 13 is a top view thereof, showing contour shading;

FIG. 14 is a bottom view thereof, showing contour shading;

FIG. 15 is a perspective view thereof, showing contour shading; and,

FIG. 16 is a second perspective view thereof, showing contour shading.

The broken lines in the drawings depict portions of the LED light that form no part of the claimed design.
